COMBINED NAIL CLIPPER AND POCKET KNIFE

Harvey N. Bliss, 106 Preston St., Windsor, Conn.

Filed Aug. 28, 1964, Ser. No. 81,492

Term of patent 14 years

(Cl. D86—10)

FIG. 1

FIG. 2

FIG. 3

FIG. 4

FIGURE 1 is a perspective view of a combined nail clipper and pocket knife showing my new design with a key chain illustrated in phantom line;

The essential features of my design reside in the portions shown in full line. Portions of the broken line showing of the key chain have been omitted from FIGURES 2-5 for convenience of illustration.

I claim:

The ornamental design for a combined nail clipper and pocket knife, as shown and described.
